UNITED STATES PATENT OFFICE.

CLAXTON E. ALLEN, OF PITTSBURGH, PENNSYLVANIA, ASSIGNOR TO WESTINGHOUSE ELECTRIC AND MANUFACTURING COMPANY, A CORPORATION OF PENNSYLVANIA.

RELAY.

1,274,660.

Specification of Letters Patent.

Patented Aug. 6, 1918.

Application filed August 6, 1915. Serial No. 44,017.

To all whom it may concern:

Be it known that I, CLAXTON E. ALLEN, a citizen of the United States, and a resident of Pittsburgh, in the county of Allegheny and State of Pennsylvania, have invented 5 a new and useful Improvement in Relays, of which the following is a specification.

My invention relates to electrical protective devices and particularly to relay mechanisms that are employed for tripping circuit interrupters or for operating other devices, upon the occurrence of predetermined 10 conditions.

The object of my invention is to provide 15 a simple and economical relay mechanism of the character indicated that may be operated by the current derived from the circuit in connection with which the interrupter or other device is employed, thereby obviating 20 the necessity of employing a separate source of power for supplying the energy and also obviating the use of contact members which are subjected to injurious arcing and the 25 possibility of welding or sticking together.

Considerable difficulty has heretofore been experienced with relay mechanisms of circuit interrupters or similar devices that are employed in connection with alternating-current circuits when it has been attempted 30 to derive currents from the said circuits for tripping or operating the interrupters. This difficulty has been due to the fact that the current for operating the relay mechanism and tripping circuit interrupter has 35 usually been derived from the main circuit by means of a series transformer, the secondary circuit of which included the operating coil of the relay, the tripping coil of the circuit interrupter, and relay contact 40 members which normally short-circuit the latter coil but are separated to permit its energization upon the occurrence of an overload or other predetermined circuit condition. There is usually a sufficient amount of 45

current in the secondary circuit to cause arcing at the relay contact members, and, at times, it may be sufficient to cause them to weld or stick together, the difficulty being most serious when there is a slow separation 50 of the contact members by reason of the employment of a dash pot or other retarding device for introducing a time interval between the occurrence of the overload and the opening of the circuit interrupter. Fur-

thermore, arcing between the contact members may so burn and injure them as to prevent them from making good electrical contact when brought into engagement. 55

I provide a tripping device that is supplied with energy from the main circuit but 60 that does not require the interruption of a circuit, thereby overcoming the hereinbefore mentioned difficulties. 65

The single figure of the accompanying drawing is a diagrammatic view of a part 65 of an electrical system embodying my invention.

A typical system, in connection with which my invention may be employed, comprises an alternating-current circuit 1 that 70 is adapted to be interrupted by means of an interrupter 2, and in series relation with one conductor of which is connected a primary winding 3 of a current transformer 4, the circuit of the secondary winding 5 of 75 which includes a winding 6 of a relay 7 and a winding 8 of a relay 9.

The relay 7 may be of any suitable construction, such as, either an instantaneous inverse or a definite time-limit relay. As 80 here illustrated, the relay 7 comprises a movable core member 10, a spring 11 for restraining said core member normally in its upward position and a bellows 12 for controlling its time of operation. The movable 85 core member 10 is operatively connected to one part 13 of the two-part magnetizable core member 14 of the relay 9, the other part 15 of which is adapted to remain stationary. The winding 8 is suitably disposed to magnetize the core member 14, and may either 90 be stationary or movable, as desired. A second winding 16 for the core member 14 of the relay 9 is inductively related to the winding 8 and is connected in circuit with 95 a trip coil 17 that is adapted to trip the circuit interrupter 2 under predetermined conditions.

Current normally traverses the windings 5, 6 and 8, but since the two parts 13 and 100 15 of the core member 14 are normally separated by air gaps, very little current is induced in the winding 16, and, consequently, the coil 17 is not sufficiently energized to trip the circuit interrupter 2. However, 105 upon the occurrence of a predetermined overload in the circuit 1, the movable core member 10 of the relay 7 will move down-

wardly, and, after a time-interval, the two portions 13 and 15 will be sufficiently close together to cause a reduction in the reluctance of the circuit of the magnetizable core member 14 and thus permit sufficient current to be induced in the winding 16 to trip the circuit interrupter 2.

While I have shown and described my invention as applied to the tripping of a circuit interrupter, a time-interval after the occurrence of pretetetermined circuit conditions, it may obviously be employed for other purposes, if desired, without departing from the spirit and scope of the invention as set forth in the appended claims.

I claim as my invention:

1. In an electrical circuit, the combination with a circuit interrupter and a tripping magnet therefor, of a time-element relay, and means adapted to be actuated by the time-element relay for causing the tripping magnet to be inductively supplied with current from the circuit.
2. In an electrical circuit, the combination with a circuit interrupter and a tripping magnet therefor, of a time-element relay, and means adapted to be actuated by the time-element relay for causing the tripping magnet to be inductively supplied with current from the circuit in accordance with the current traversing the said time-element relay.
3. In an electrical circuit, the combination with a circuit interrupter and a tripping magnet therefor, of a relay comprising a magnetizable core member normally having air gaps therein, a primary winding operatively connected to the circuit, a secondary winding connected in closed-circuit relation to the tripping magnet, and time-retarded means for decreasing the air gaps when a predetermined current traverses the circuit to thereby energize the tripping magnet.
4. In an electrical circuit, the combination with a circuit interrupter and a tripping magnet therefor, of a relay comprising a magnetizable core member normally having air gaps therein, a primary winding operatively connected to the circuit, a secondary winding connected in closed-circuit relation to the tripping magnet, and time retarded means connected in circuit with the primary winding for decreasing the air gaps when a predetermined current traverses the circuit to thereby energize the tripping magnet.
5. In an electrical circuit, the combination

with a circuit interrupter and a trip coil therefor, of a time-element relay, an electromagnetic device having a main winding connected in series with the winding of the relay and a secondary winding operatively connected to the trip coil, and means whereby the electromagnetic device is actuated by the relay to cause currents to be induced in the secondary winding and the trip coil in accordance with the current traversing the circuit.

6. In an electrical circuit, the combination with a circuit interrupter and a trip coil therefor, of a time-element relay, a two-part magnetizable core member having a main winding connected in series with the relay and a secondary winding connected in closed-circuit relation to the trip coil, and means whereby the relay is adapted to so actuate the two-part magnetizable core member that sufficient current is induced in the secondary winding from the circuit to trip the interrupter under predetermined conditions.

7. In an electrical circuit, the combination with a circuit interrupter and a trip coil therefor, of a time-element relay, a two-part magnetizable core member, a main winding on the two-part core member connected in series with the relay and supplied with current from the circuit, a secondary winding on the said two-part core member connected in closed-circuit relation to the trip coil, and means whereby the relay is adapted to cause sufficient current to be induced in the secondary winding to trip the interrupter.

8. In an electrical circuit, the combination with a circuit interrupter, a tripping magnet therefor, and a time-element relay, of a second relay comprising a two-part magnetizable core member, a primary winding operatively connected to the circuit and a secondary winding operatively connected in circuit with the tripping electromagnet, said time-element relay being adapted to move the parts of the magnetizable core member relatively to each other a time interval after a predetermined current traverses the circuit.

In testimony whereof, I have hereunto subscribed my name this 22nd day of July, 1915.

CLAXTON E. ALLEN.
